UNITED STATES PATENT OFFICE.

ALBERT C. BOOTH, OF CEDAR RAPIDS, IOWA, ASSIGNOR OF ONE-HALF TO
WILLIAM P. WARD, OF SAME PLACE.

TELEGRAPH-REPEATER.

SPECIFICATION forming part of Letters Patent No. 451,449, dated May 5, 1891.

Application filed August 24, 1889. Renewed March 21, 1891. Serial No. 385,847. (No model.)

To all whom it may concern:

Be it known that I, ALBERT C. BOOTH, of Cedar Rapids, in the county of Linn and State of Iowa, have invented certain new and useful Improvements in Telegraph-Repeaters, of which the following is a specification.

The improved repeater is illustrated in the accompanying drawings, in which—

Figure 1 is a diagram showing the electrical circuits and the mode of operation, and Fig. 2 is a perspective view of the repeating mechanism.

In the drawings only the instruments at the repeating-station are shown. In the subsequent description, for the sake of clearness and brevity, it will be considered that a message is to be transmitted from a station to the right of the repeating-station to a station to the left, though of course messages can be transmitted in either direction. From the transmitting-station a line-wire 1 leads to a key A at the repeating-station, and the key A is connected by wire 2 to a fixed metallic contact or electrode B. A metallic spring-key C is normally in contact with the electrode B. A wire 3 connects the key C with a relay-magnet D, and the relay-magnet is connected to earth by a wire 4, thus completing the circuit to the transmitting-station, which is equipped with the ordinary Morse instruments. The circuit from the transmitting-station is normally a closed one. In close proximity to the electrode B is a second metallic contact or electrode B², which is normally in metallic contact with a spring-key C². The spring-key C² is connected by a wire 5 to a relay-magnet D², which is connected to earth by a ground-wire 6. The electrode B² is connected by a wire 7 to a key A², from which leads a line-wire 8 to the receiving-station provided with the usual Morse instruments. The circuit through the receiving-station is thus also normally a closed one.

E E² are the repeating-magnets, and F F² are their armatures. The armatures F F² are mounted on opposite ends of a balanced oscillating lever G, centrally pivoted in suitable bearings. The lever G is a balanced one, so that normally both armatures are out of contact with their respective magnets. The lever G carries a crank-arm H, of insu-

lating material, which rests normally between the two spring-keys C C² and in contact with both, whereby the lever G is maintained in its proper balanced position.

55

R is the repeater-battery, one pole of which is connected by a wire 9 with both of the repeater-magnets E E². A normally-closed switch I is located in the wire 9. The opposite pole of the battery is connected by wires 10 and 11, respectively, to the swinging armatures J J² of the relay-magnets D D², respectively.

The armatures J J² are carried, respectively, by pivoted metallic levers K K², the armatures and their respective levers being preferably insulated from each other. Since the circuits through the relay-magnets are normally closed, their armatures J J² are consequently normally attracted toward them, 70 with the free ends of the levers K K² normally in metallic contact with contacts or electrodes L L², respectively. The electrode L is connected by a wire 12 with a sounder-magnet M, which is connected by a wire 13

with one pole of a local battery N, the other pole of which is connected by a wire 14 with the lever K. The local circuit through the sounder-magnet is thus a normally-closed one. In a similar manner the electrode L² is connected by wire 15 with sounder-magnet M², which is connected by wire 16 with one pole of a local battery N², the other pole of which is connected by wire 17 with the lever K². Behind, but out of contact with the levers K

K², respectively, are adjustable coating contacts or electrodes O O², which are mounted in metallic brackets P P². The bracket P is electrically connected by wire 18 with the repeater-magnet E, and a wire 19 connects the repeater-magnet E² with the bracket P².

If now the circuit is broken at the transmitting-station, the relay-magnet D will be demagnetized and the armature J will drop back, and its lever K will make electric connection 95 with the electrode O. By so doing the circuit through bracket P, wire 18, repeater-magnet E, wire 9, switch I, repeater-battery R, wire 10, lever K, and electrode O will be closed, thus exciting the magnet E. The magnet E, being excited, attracts its armature F, thus swinging the balanced lever G

and moving its crank-arm H in the direction of the spring-key C², thus moving the latter out of contact with the electrode B². This disconnection of the key C² and electrode B² 5 operes the circuit through wire 5, relay-magnet D², ground-wire 6, the earth, the receiving-station, line-wire 8, key A², and wire 7, thus actuating the receiving-instrument at the receiving-station. At the same time the 10 falling back of armature J and lever K breaks the local circuit through the sounder-magnet M at the repeating-station. The closing of the circuit at the transmitting-stations excites magnet D, thus breaking the circuit through 15 repeater-magnet E, demagnetizing the same, so that the lever G resumes its normal position under the action of the spring-key C², which again touches electrode B², and so closes the circuit through the receiving-station. 20 The excitation of magnet D also closes the local circuit through the sounder-magnet M. Thus the opening and closing of the circuit at the transmitting-station operates a sounder at the repeating-station, and by means of the 25 repeater the circuit to the receiving-station is similarly opened and closed. The transmission of the message through the receiving-station actuates also the other sounder M' at the repeating-station, since the relay-magnet 30 D² is excited and demagnetized by the opening and closing of the circuit through the receiving-station. The operator at the repeating-station can thus always tell whether or not the repeater is working properly. By 35 means of the keys A A² messages can be transmitted from the repeating-station either way. By means of the switch I the circuit through the repeater may be thrown off and the straight circuit used between the repeater- 40 station and either of the other stations when the repeater is not to be used. It will be observed that each sounder M M² will operate independently of the repeater.

I claim as my invention—

45 1. Two relay-magnets D D², two fixed electrodes B B², two spring-keys C C², coacting, respectively, with said electrodes at a repeating-station, and two normally-closed electric circuits extending to two distant stations, one 50 of said relay-magnets, electrodes, and spring-keys being located in each of said circuits, in combination with metallic pivoted levers K K², respectively carrying the armatures J J²

of the said respective relay-magnets D D², electrodes O O², coacting with said levers K K², respectively, but normally out of contact therewith, a repeater-battery R, wires connecting one pole of said battery with said levers K K², respectively, repeater-magnets E E², connected by wires with said electrodes O O², respectively, both of said magnets being also connected with the opposite pole of said battery, a balanced swinging lever carrying on opposite ends the armatures of said magnets E E², and a crank-arm carried by said lever and located in co-operative relation between both of said spring-keys C C², substantially as set forth. 55 60 65

2. Two relay-magnets D D², two fixed electrodes B B², two spring-keys C C², coacting, respectively, with said electrodes at a repeating-station, and two normally-closed electric circuits extending to two distant stations, one of said relay-magnets, electrodes, and spring-keys being located in each of said circuits, metallic pivoted levers K K², respectively carrying the armatures J J² of the said respective relay-magnets D D², electrodes O O², coacting with said levers K K², respectively, but normally out of contact therewith, a repeater-battery R, wires connecting one pole of said battery with said levers K K², respectively, repeater-magnets E E², connected by wires with said electrodes O O², respectively, both of said magnets being also connected with the opposite pole of said battery R, a balanced swinging lever carrying on opposite ends the armatures of said magnets E E², and a crank-arm carried by said lever and located in co-operative relation between both of said spring-keys C C², in combination with electrodes L L², co-operating with said levers K K² and arranged to be in contact therewith when the relay-magnets D D² are excited, two local electric circuits, one of said levers K K², one of said electrodes L L², and one of two sounder-magnets M M² being located in each of said local circuits, respectively, substantially as set forth. 70 75 80 85 90 95

In witness whereof I have hereunto signed my name in the presence of two subscribing witnesses.

ALBERT C. BOOTH.
